(57) **CLAIM**

The ornamental design for a planter base attachment, as shown and described.

DESCRIPTION

FIG. 1 is a front elevational view of a design for a planter base attachment, showing my new design. The rear view is a mirror image of the front elevational view.

FIG. 2 is a top plan view of the planter base attachment.

FIG. 3 is a bottom plan view of the planter base attachment.

FIG. 4 is a right elevational view of the planter base attachment. The left elevational view is a mirror image of the right elevational view.

FIG. 5 is a perspective view of the planter base attachment; and,

FIG. 6 is a cross-sectional view of the planter base attachment made by cutting along the line A-A in FIG. 2.

1 Claim, 6 Drawing Sheets
